UNITED STATES PATENT OFFICE

2,463,692

PIN OR CLASP

Crofton C. Holden, Leominster, Mass., assignor to
 Tilton & Cook Co., Leominster, Mass., a corporation of Massachusetts

Application October 24, 1944, Serial No. 560,099

1 Claim. (Cl. 24—160)

1

The present invention relates to pins or clasps such as are useful as barrette pins and the like.

The object of the present invention is to provide an all-plastic pin which can be inexpensively manufactured and which is capable of being securely clasped.

With this object in view, the present invention comprises the pin or clasp hereinafter described and particularly defined in the claim.

In the accompanying drawings, Fig. 1 is a plan view of the pin; Fig. 2 is a sectional elevation; and Fig. 3 is a detail view of the tongue member.

The pin comprises a base member 4 and a tongue member 6, both preferably made entirely of molded plastic.

The base 4 has a hook 8 on one end to engage the end of the tongue, and a hinge portion, indicated at 10, at the other end. The hinge portion comprises two separated side walls 12, into which a lateral slot 14 extends upwardly through the base. The space between the walls 12 is partly filled above the top of the base, to form a front wall indicated at 16 of considerably less height than the side walls 12, for a purpose to be explained later.

The tongue 6, as shown in Fig. 3, is flared outwardly from its point toward the rear, where it is reduced in width to form a retaining portion 18 of the proper size to lie between the side walls 12 of the base member. At the extreme rear of the tongue member, there is provided a rod-shaped portion 20, serving as a pivot. The entire tongue member is thus generally T-shaped.

The tongue portion is assembled in the base portion by simply pushing the tongue upwardly through the slot 14. The flared portion of the tongue spreads the walls 12 until the portion 18 snaps into place between the walls. Thereafter, the tongue member is free to pivot on the rod portion 20.

The front wall 16 between the walls 12 is suffi-

ciently high so that the end of the tongue cannot be snapped into the hook without applying a substantial bending stress to the tongue member. The tongue may be bent slightly sidewise and downwardly to enter into the hook, after which the resilience of the tongue under the pressure of the portion 16 causes the end to engage firmly under the hook.

10 The pin described above may be cemented or otherwise applied to a barrette or other ornament, indicated in dot and dash lines at 22 in Fig. 1.

Having thus described my invention, I claim:

15 A pin or clasp comprising a base of plastic material having a tongue-engaging hook and a hinge portion, the hinge portion comprising two separated side walls, said base having a slot which extends across said base and upwardly into the side walls, a front wall extending upwardly from the base between the two side walls, and a T-shaped tongue member having a rod-shaped pivot portion insertable through said slot, a flaring tongue, and a portion of reduced size adjacent the rod-shaped portion, the rear portion of the tongue being wider than the space between the side walls, the reduced portion of the tongue member being disposed between the side walls and engaging the front wall to stress the tongue to hold it in engagement with the hook.
